PREPARATION OF FEED MATERIAL FOR
THE CONVERSION OF HYDROCARBONSWilfred O. Taff, Cranford, and John Weikart,
Elizabeth, N. J., assignors to Standard Oil De-
velopment Company, a corporation of Delaware

Application January 3, 1949, Serial No. 68,938

2 Claims. (Cl. 196—73)

1

This invention pertains to a method of converting hydrocarbon materials and particularly to the conversion of residual stocks in order to form substantial quantities of high quality feed for catalytic cracking operations.

In order to prepare feed stocks for catalytic cracking operations it is common practice in the art to subject petroleum crude oil to an atmospheric distillation in order to obtain a gas oil fraction, generally boiling between about 430° F. and about 800°—900° F., and a higher boiling residuum which will normally equal about up to about 20-30 vol. % of the original feed. This residuum does not represent a satisfactory catalytic cracking stock and accordingly efforts have been made to convert it or obtain additional amounts of gas oil therefrom which would be suitable as feed stocks for a catalytic cracking system. The method of converting this higher boiling residual stock ordinarily is a thermal cracking or visbreaking operation. It has been found however that the gas oil produced in the normal visbreaking operation is a poor catalytic cracking feed stock. The terms "visbreaking" and "visbreaker" used herein are synonymous with the terms viscosity breaking and viscosity breaker respectively.

It is the object of this invention to provide the art with an improved method for treating higher boiling residual stocks from the atmospheric distillation of petroleum crude oils.

It is a further object of this invention to provide the art with a method for treating higher boiling residual stocks from the atmospheric distillation of petroleum crude oils which increases the quantity and improves the quality of the gas oil formed to make it suitable as a feed stock to a catalytic cracking operation.

These and other objects will appear more clearly from the detailed specification and claims which follow.

It has now been found that the foregoing objects can be fulfilled if the residual stock is passed into a tower maintained substantially below atmospheric pressure and which has its bottom section divided into two sections by means of a dam or partition. The residue from the atmospheric distillation is supplied to one of the sections in the bottom of the vacuum tower wherein it is further reduced, or additional amounts of gas oil are stripped therefrom. The stripped residue is then subjected to a visbreaking operation. The visbreaker is preferably of the coil-only type where relatively high temperatures and short contact times can be em-

ployed. However, the coil and drum type or a coil and swinging drum visbreaker could be used in which latter case all of the cracked bottoms are recycled and the drums allowed to cake. The reaction products from the visbreaker are fractionated in an atmospheric fractionating tower to separate visbreaker gas and gasoline and a visbreaker residuum. This residuum is recycled to the vacuum tower preferably to the other of the two sections in the bottom of the tower where it is stripped of gas oil formed in the visbreaking operation whereupon the visbreaker gas oil is combined with the gas oil from the virgin residuum and passed to a catalytic cracking unit.

15 The stripped visbreaker residuum is withdrawn from the second section of the vacuum tower partly as a purge stream and partly to be combined with the stripped virgin residuum and recycled to the visbreaker.

20 Reference is made to the accompanying drawing wherein a schematic flow diagram of the process of the present invention is shown.

In the drawing, 10 is a supply line through which virgin residuum from an atmospheric distillation of a petroleum crude oil is passed, at elevated temperatures into vacuum tower 11. A partition or dam 12 is arranged in the bottom of vacuum tower 11 in order to divide the bottom portion of the tower into two sections 13 and 14. The virgin residuum is supplied to section 13 and because of the low oil partial pressure maintained in the tower because of the vacuum and stripping steam, further quantities of gas oil are vaporized and taken overhead from 35 the vacuum tower 11 through outlet line 15.

An outlet line 16 is arranged at the bottom of the tower 11 for the withdrawal of stripped residuum from section 13. The stripped residuum withdrawn from section 13 is then pumped 40 through line 17 which passes through furnace 18 wherein the stripped virgin residuum is heated to conventional visbreaking temperatures of about 800°—950° F. at the coil outlet. If a coil and drum type of visbreaking operation is em- 45 ployed, the temperature at the coil outlet will ordinarily be between 800° and 900° F.

The visbreaker products are discharged through line 19 into atmospheric distillation column 20 from which visbreaker gas and gasoline are taken overhead through line 21 while a residuum is withdrawn from the bottom of column 20 and passed through line 22 into section 14 in the bottom of vacuum tower 11 wherein it is vacuum stripped of gas oil formed in the vis- 55 breaking step. The visbreaker gas oil is with-

drawn in admixture with the gas oil that is stripped from the virgin residuum through outlet 15 and may then be passed to a catalytic cracking operation.

A portion of the stripped, cracked or visbreaker residuum may be withdrawn from section 14 through line 23 and recycled to the visbreaker through line 17 along with the stripped virgin residuum. However, in view of the high ash and carbon residue content of the cracked residuum it is preferable to remove a portion of this stream from the system through purge line 24 for use as fuel oil.

The present process is applicable to any residual stocks obtained by the atmospheric distillation of crude petroleum oil. As a rule the residuum will comprise at most about 20-30 vol. percent of the original oil and will have a boiling range above about 800°-900° F. The residual stocks as withdrawn from the atmospheric distillation operation will ordinarily be at a temperature of at least about 600° F. If the oil is too cool to flash off appreciable quantities of gas oil when placed under reduced pressure in the vacuum tower, the residuum can be subjected to a preheating operation to bring its temperature up to the desired operating level of about 600° to about 800° F.

The pressure maintained in the vacuum tower 11 is ordinarily below about 50 mm. Hg. In order to reduce the oil partial pressure in the vacuum tower to below about 15 mm. Hg, further stripping steam may be introduced through steam inlets 25 in the bottom of the vacuum tower 11.

The stripped virgin residuum is heated in furnace 18 to the maximum temperature permissible without deposition of coke on the coils. Ordinarily, the coil outlet temperature in a coil-only visbreaker is between 900°-925° F., while with other types of visbreakers, the temperature level is generally about 50° F. lower.

The following example will serve to illustrate the improvement in yield and quality as a feed stock for a catalytic cracking operation of gas oils obtainable from a residual stock in accordance with the present invention.

EXAMPLE

A 16% residuum obtained from the atmospheric distillation of a West Texas crude having a gravity of about 10° A. P. I., a Conradson Carbon of about 15 wt. per cent and a viscosity of 1250 Saybolt Universal seconds at 210° F. was subjected to vacuum distillation at about 6 mm. Hg and a temperature of 770° F. The residue from this vacuum distillation was then thermally cracked and the gas and gasoline formed in this thermal cracking operation were separated from the visbreaker residuum. The latter was subjected to vacuum distillation under the same conditions as applied to the virgin residuum. The gas oil separated from the visbreaker residuum was combined with the virgin gas oil vacuum stripped from the original residuum and the mixture was then catalytically cracked by contacting it with a silica-alumina cracking catalyst at 975° F. to a conversion of 55%.

Another portion of the same 16% residuum was subjected directly to a thermal cracking operation. The gas and gasoline formed were separated from the reaction product and the residuum was subjected to vacuum distillation at about 6 mm. Hg and a temperature of 770° F. The gas oil obtained was then catalytically cracked under the same conditions as the mix-

ture of virgin and thermally cracked gas oil as described above. The results obtained are summarized in the following table:

Table

Residuum Treatment	Vacuum Distillation Visbreaking and Vacuum Distillation of Visbreaker Residue	Visbreaking and Vacuum Distill. of Visbreaker Residue
Gas Oil for Cat. Cracking-- Percent on Original Residuum:		
Virgin, percent	48.8	57.6
Thermally Cracked, do	22.5	
Vacuum Still Bottoms:		
Percent on Residuum	26.2	30.0
Specific Gravity	1.12	1.11
Softening Point, °F.	260	240
Cat. Cracking Yields (Based on Gas Oil):		
Gasoline, Vol. percent	45.9	41.0
Excess Butane-Butylene, Vol. percent	3.4	6.3
Dry Gas (C ₄ free) wt. percent	8.3	8.0
Carbon, wt. percent	6.0	7.4
Conversion	55.0	55.00
Gasoline Yields, Vol. percent Based on Residuum	32.7	23.6

These data show that a substantial increase in gas oil is obtained by the process in accordance with the present invention and that it is a better catalytic cracking feed stock as shown by the higher gasoline yields based not only on the residuum but also on the gas oil charged, and showed substantially less carbon formation.

It may be seen from the foregoing description that the process in accordance with the present invention makes it possible to avoid thermal cracking and/or degradation of any virgin gas oil that is capable of being vacuum stripped from the original residuum and permits the vacuum flashing of the virgin residuum and visbreaker residuum in a single vacuum tower without contamination of the stripped virgin residuum.

The foregoing description contains a limited number of embodiments of the present invention. It will be understood that numerous variations are possible without departing from the scope of the following claims.

What is claimed is:

1. A process for the production of high quality feed for catalytic cracking from residual stocks which comprises subjecting a petroleum crude oil to distillation at atmospheric pressure to separate light constituents and a gas oil fraction boiling from about 430° F. to 800-900° F. forming higher boiling virgin residual stock constituting about 20-30% of the original petroleum crude oil, passing said virgin residual stock to a primary stripping zone maintained at a pressure substantially below atmospheric pressure in order to remove further quantities of virgin gas oil therefrom, subjecting the stripped virgin residual stock to visbreaking, subjecting the reaction product from the visbreaking step to atmospheric distillation to separate visbreaker gas and gasoline from visbreaker residue, passing the visbreaker residue to a separate compartment of the primary stripping zone in order to strip visbreaker gas oil from the visbreaker residue, combining the visbreaker gas oil with the gas oil stripped from said virgin residual stock, recycling a part of the stripped visbreaker residue to the visbreaking step, and removing a sufficient amount of the stripped visbreaker residue from the system to prevent excessive accumulation of ash and carbon residues therein.
2. A process for the production of high quality

feed for catalytic cracking from residual stocks which comprises passing virgin residual stock, from a distillation operation wherein lighter products including a gas oil fraction boiling up to 800° to 900° F. has been removed, to a primary stripping zone under substantially subatmospheric pressure to remove as much additional gas oil as possible from said virgin residual stock, passing the stripped residual stock to a vis-breaker and subjecting to mild vis-breaking treatment for a short contact time to produce further gas oil and lighter products, passing the vis-broken stock to an atmospheric distillation zone to strip said lighter products, passing the stripped stock to a sub-atmospheric separating zone operating under essentially the same conditions as said primary stripping zone to separate gas oil therefrom, combining said separated gas oil with the above mentioned additional gas oil, withdrawing the bottoms from said separating zone, removing part of said bottoms from the system and recycling the remainder of said bottoms to the vis-breaker, atmospheric distillation and separating zones, to maximize gas oil yield

5 with a minimum of cracking of said gas oil in the vis-breaking operation.
